(57) **CLAIM**

The ornamental design for a hatching dinosaur mechanized toy, as shown and described.

DESCRIPTION

FIG. 1 is a left frontal perspective view of a hatching dinosaur mechanized toy, showing my new design;

FIG. 2 is a rear perspective view;

FIG. 3 is a frontal perspective view, showing an egg of the design in closed configuration;

FIG. 4 is a right frontal perspective view; and,

FIG. 5 is a top view.

The bottom view is specifically disclaimed.
